DESIGN FOR A BEVERAGE COOLER

Charles Kavalir, New York, N. Y.

Application May 26, 1938, Serial No. 77,410

Term of patent 7 years

To all whom it may concern:

Be it known that I, Charles Kavalir, a citizen of the United States and resident of New York, in the county of Queens, State of New York, have invented a new, original, and ornamental Design for a Beverage Cooler, of which the following is a specification, reference being had to the accompanying drawing, forming part thereof, and in which the figure is an elevation of the beverage cooler showing my new design.

The characteristic features of the design reside in a beverage cooler having the configurations, proportions and arrangement of parts, substantially as shown.

I claim:

The ornamental design for a beverage cooler, as shown and described.

CHARLES KAVALIR.
